UNITED STATES PATENT OFFICE.

FRANK M. BASHAM AND JAMES O. DONALDSON, OF CHUALAR, CALIFORNIA, ASSIGNEES TO SOUTHERN PACIFIC MILLING COMPANY, OF SAN FRANCISCO, CALIFORNIA, A CORPORATION OF CALIFORNIA.

HOISTING APPARATUS.

No. 926,314.

Specification of Letters Patent.

Patented June 29, 1909.

Application filed February 24, 1908. Serial No. 417,242.

To all whom it may concern:

Be it known that we, FRANK M. BASHAM and JAMES O. DONALDSON, citizens of the United States, residing at Chualar, in the county of Monterey and State of California, have invented certain new and useful Improvements in Hoisting Apparatus, of which the following is a specification.

The present invention relates to an improved hoisting apparatus for the loading and unloading of sacks of grain or other articles, it being mainly designed for use in warehouses in connection with the raising of sacks of grain to be stacked therein.

The essential features of the invention reside in the means for automatically disconnecting the friction disks from the driving cone of the power shaft the moment the lifting or haulage cable has been brought into position for either the securing of a sack thereto for the hoisting thereof, or for the releasing of a sack therefrom after the same has been raised or elevated its required height; in the employment of adjustable trip collars for automatically actuating the lever controlling the longitudinal movement of the slideable drive shaft to disconnect the friction disks on the hoisting cable reaching its desired position; and in the utilization of longitudinally movable adjustable sleeves which carry the trip collars and regulate the movement thereof for actuating the controlling lever, said adjusting sleeves being driven by means of a feed shaft.

To comprehend the invention reference should be had to the accompanying sheets of drawings, wherein—

Figure 1 is a plan view of the apparatus. Fig. 2 is a side view in elevation of the mechanism contained in Fig. 1 of the drawings. Fig. 3 is a rear end view of the apparatus. Fig. 4 is a front view of the apparatus, the frame thereof being broken away.

In the drawings, reference being had to Figs. 1 and 2 thereof, the numeral 1 is used to designate any suitable form of a frame for the hoisting mechanism, on which is mounted, in the present case, a gasoline motor engine 2. To the inner end of the power shaft 3 of the said engine is secured a cone 4, which frictionally engages with the disks 5—5'. These disks are mounted on a longitudinally movable drive shaft 6, which drive shaft works in bearings se-

cured to the end portions of the frame 1. On the drive shaft 6, and within the frame 1 is secured a hoisting drum 7, and a short distance beyond the said drum 7 there is also secured on the drive shaft 6 a brake wheel 8. To the outer end of the drive shaft 6 is secured a sprocket wheel 9, which is connected to or with an upper sprocket wheel 10 by means of a drive chain 11. The upper sprocket wheel 10 is secured to the outer 65 projecting end of a feed shaft 12, which shaft receives its motion from the drive shaft 6 by means of the chain 11. Above the feed shaft 12 and to each side thereof the square or angular shaped longitudinally disposed 70 guide rods 13—14 are located, the bearing portions 15 of which are rounded to turn within the bearings 15' carried by the upper cross end pieces of the frame 1. On the said guide rods 13—14 are slidably mounted 75 respectively the externally screw-threaded adjusting sleeves 16—16', which sleeves are reciprocated on the guide rods 13—14 by means of the brackets 17—17'. The upper end of each bracket lies within the grooved 80 end portion 18 of the sleeves 16—16', the lower end portion of each of the said brackets having a screw-threaded bore through which works the screw-threaded portion 18' of the feed shaft 12. The said adjusting 85 sleeves 16—16' carry respectively the internally screw-threaded trip collars 19—19', which collars, during the reciprocating movement of the said sleeves 16—16', act against the vertically disposed lever 21, to throw the 90 same to shift the position of the longitudinally movable slide drive shaft 6, so as to place the disks 5—5' respectively into frictional engagement with the cone 4 of the power shaft 3. 95

Each of the guide rods 13—14 has secured thereto a handle 21', by means of which the said rods are rotated to turn the adjusting sleeves 16—16'. As rotation is imparted to these adjusting sleeves by the 100 turning of the guide rods 13—14 to either the right or left, the trip collars 19—19' are correspondingly advanced toward or from the controlling lever 21, so as to act against the same at an earlier or later portion of the movement of the adjusting sleeves 16—16', to operate the same to actuate the drive shaft 6 for automatically disconnecting the disks 5—5' from frictional engagement with the cone 4. The controlling lever 110

21 at its lower end is pivoted to a collar 22 attached to the drive shaft 6, and at its upper end it is connected to the operating lever 22' by means of the connecting 5 rod 23, the said controlling lever 21 being also fulcrumed to a fixed bracket 23' by the link 24.

The tail extension of each trip collar 19-19' is slidable on a longitudinally disposed guide rod 24', which rod acts as a support for the tail extension of the said trip collars and holds the same against rotation during the turning action of the adjusting sleeves 16-16' to adjust the position 10 of the said collars relative to the controlling lever 21, which lever, as stated, is automatically actuated by the said trip collars to shift the position of the drive shaft 6 to release the disks 5-5' from frictional 15 engagement with the cone 4, the releasing of which disks destroys the movement imparted to the said drive shaft, and the transmission of motion from said shaft to the feed shaft 12.

To the upper end of the controlling lever 25 21 is connected an outwardly extending 21' brake actuating rod 25', to which rod is secured a companion rod 25'. These rods work respectively through the arms 26-26' of the bell crank 27, pivoted to the rear end 30 portion of the frame 1. The said bell crank 27 is connected by a link 28 to an arm 28', fulcrumed to a stud 29 projecting from one section 29' of the brake-band, the opposing section 30 of which is connected to upwardly flanged extension 30' of the arm 28' 35 by the link 31. On the outer portion of the arm 28' is adjustably secured the weight 32, which is sufficient to normally hold the said arm downward in order to compress or 40 draw together the sections 29'-30 of the brake band and cause the same to place the brake-shoes 33 onto the brake-wheel 8 to hold the same and the shaft 6 locked against movement, Fig. 3 of the drawings. As 45 the lever 21 is thrown by the action of the lever 22' to place the disk 5 into frictional engagement with the cone 4, the nut 34 on the rod 25' bears onto the arm 26' of the bell crank 27, and throws the said bell crank to 50 raise the weighted arm 28', causing the same by its action to open the sections 29'-30 of the brake band and to release the brake shoes 33 from engagement with the 55 brake wheel 8; while on the controlling lever 21 being thrown by the operating lever 22' to place the disk 5' into frictional engagement with the drive cone 4 on the power shaft 3, the nut 35 on the rod 25' acts against the lower arm 26 of the bell crank 27 to raise 60 the weighted arm 28' in order to force apart the sections 29'-30 of the band-brake to release the brake-wheel 8. The moment either disk 5 and 5' is moved out of frictional engagement with the cone 4 of the power shaft 65 3, by the action of the controlling lever 21

through the medium of the trip collars 19-19', as hereinbefore explained, the weight 32 serves to throw downwardly the arm 28', which, through its movement draws together the sections 29'-30 of the brake band, and applies the brake shoes 33 onto the brake wheel 8, to hold the drive shaft 6 against rotation.

As the adjusting sleeve 16 is moved toward the controlling lever 21 to carry its 75 trip collar 19 against the said lever to actuate the same to move the slidable drive shaft 6 so as to disengage the disk 5' from the cone 4, the adjusting sleeve 16' is moved away from the said controlling lever 21; while as the adjusting sleeve 16' approaches the controlling lever 21 to actuate the same to move the drive shaft 6 to disengage the disk 5 from the cone 4, the adjusting sleeve 16 is moved away from the said lever 21. 85 These adjusting sleeves are moved inwardly and outwardly by the rotation of the feed shaft 12, the direction of its rotation being controlled in accordance as to which of the disks 5-5' is in frictional engagement with 90 the cone 4.

Having thus described the invention, what is claimed as new and desired to be protected by Letters Patent is—

1. In an apparatus of the described character, the combination with the feed shaft thereof, a slidable drive shaft, means for imparting rotation to the drive shaft, connection between the drive shaft and the feed shaft, of longitudinally movable adjusting sleeves actuated by the feed shaft, a controlling lever for the drive shaft, hand operated devices for throwing the said lever to place the drive shaft into engagement with its drive mechanism, trip collars carried by the 100 adjusting sleeves, said collars acting to automatically throw the controlling lever to disconnect the drive shaft from its operating mechanism, and means for actuating the adjusting sleeves to vary the position of the 110 trip collars relatively thereto.

2. In an apparatus of the described character, the combination with the controlling lever, of reciprocating adjusting sleeves, means for imparting reciprocating motion 115 thereto during the working of the apparatus, trip collars carried by the said adjusting sleeves for acting against the controlling lever for the described purpose, and devices for actuating the adjusting sleeves to vary the position of the trip collars relatively 120 thereto.

3. In an apparatus for the described purpose, the combination with the controlling lever thereof, of longitudinally movable adjusting sleeves, trip collars carried thereby 125 for automatically throwing the controlling lever for the described purpose, a feed shaft for imparting reciprocating motion to the adjusting sleeves, means for actuating the 130

said adjusting sleeves to regulate the position of the trip collars relatively thereto, brake mechanism for holding the drive shaft of the apparatus against movement, and connections between the said brake mechanism and the controlling lever for throwing the same into and out of action with the movement of the said lever.

4. In an apparatus of the described character, the combination with the drive shaft, of mechanism for imparting rotation thereto, a controlling lever for shifting the drive shaft, hand actuated devices for throwing the said controlling lever to connect the drive shaft with its mechanism for imparting rotation thereto, a drum on the drive shaft, adjustable trip collars for operating the controlling lever to disconnect the drive shaft from its operating mechanism, means for actuating the trip collars from the drive shaft, and devices for adjusting the position

of said collars relative to the controlling lever.

5. In an apparatus of the described character, the combination with a slideable drive shaft, of mechanism for imparting rotation thereto, a controlling lever for said shaft, hand actuated devices for throwing said lever to connect the drive shaft with the mechanism for imparting rotation thereto, a drum secured to the drive shaft, and adjustable means for automatically operating the controlling lever to disconnect the drive shaft from its rotating mechanism.

In testimony whereof we have signed our names to this specification in the presence of two subscribing witnesses.
